United States Patent Office

Des. 210,758
Patented Apr. 9, 1968

210,758

VEHICLE

Walter E. Binder, 5805 St. John St.,
Kansas City, Mo. 64123

Filed June 26, 1967, Ser. No. 7,599

Term of patent 14 years

(Cl. D90—8)

Fig. 1.

Fig. 2.

Fig. 3.

Fig. 4.

Fig. 5.

FIG. 2 is a side elevational view thereof;

FIG. 3 is a fragmentary elevational view showing the side thereof opposite that shown in FIG. 2, the parts not appearing in FIG. 3 being substantially identical to the corresponding parts shown in FIG. 2;

FIG. 4 is a front elevational view thereof; and

FIG. 5 is a rear elevational view thereof.

I claim:

The ornamental design for a vehicle, as shown and described.
